CLEANING MACHINE

William Ralph Fitzgerald and Andrew Docken,
Chicago, Ill.

Application August 17, 1938, Serial No. 225,402

4 Claims. (Cl. 15—50)

This invention relates to improvements in cleaning machines and more particularly to the type employing a power driven rotary brush.

One of the objects of this invention is the provision of a power driven cleaning machine which is adapted for cleaning floors, rough surfaces and the like.

Another object is the provision of a power driven cleaning machine which is adapted to be 10 used both for sweeping and washing of floor surfaces.

A further object of this invention is the provision of a cleaning machine which is simple in construction, highly efficient in operation, and 15 which can be constructed and operated at low cost.

With the foregoing and other objects in view, the invention consists of the novel construction, combination and arrangement of parts as hereinafter more specifically described and illustrated in the accompanying drawings.

In the drawings wherein like reference characters denote corresponding parts through the several views:

25 Fig. 1 is a side elevational view of a cleaning machine constructed in accordance with the present invention.

Fig. 2 is a top plan view of same.

Fig. 3 is a cross sectional view taken on line 20 3—3 of Fig. 2.

Fig. 4 is a front elevational view of the device shown in Fig. 1.

Fig. 5 is a cross sectional view taken on line 5—5 of Fig. 1.

35 Fig. 6 is a fragmentary side elevational view partly in cross section showing the positioning of tank containing the washing fluid compound.

Fig. 7 is a front elevational view showing the fluid discharge mechanism.

40 Fig. 8 is an enlarged fractional view taken on line 8—8 of Fig. 4.

Referring to the drawings the preferred embodiment of our invention comprises a frame 10 on which is supported a housing 11. The frame 45 10 is formed of two downwardly inclined side arms 12 and 13 and a transverse bar 14 adapted to serve as a handle bar. A bracing bar 16a is secured to the side arms 12 and 13 and to the rear portion of the housing 11. Said housing 11 is 50 formed of an arcuate shield 16 and side members 17 and 18 welded thereto. The side members 17 and 18 have forwardly extending portions 17a and 18a to which are secured the side arms 12 and 13 respectively. A transverse bar 15 secured 55 to the forward portions 17a and 18a serves as a

brace for same. Mounted on said portions 17a and 18a and projecting outwardly thereof are short shafts 19 and 20 which serve as axles for the rubber tired carrying wheels 19a and 20a respectively.

5 Mounted rearwardly of the housing 11 on the arcuate shield 16 is a vertical bearing member 21. Rotatably and slidably mounted in said bearing member is a vertical shaft 22 having at one end a yoke member 23 in which is journaled a rear trailer wheel 24. The upper portion of the shaft 22 is provided with a concave recess 22a which is adapted to bear against a ball bearing 25. Threaded into the upper portion of the bearing member 21 is an adjusting rod 26 which is provided with wheel 27. The lower end of said adjusting rod is adapted to bear against a slidably mounted member 28 which is provided with a concave surface 28a to receive the ball bearing 25. It will thus be seen that by means of the wheel 20 27 the height of the brush 31 with respect to the floor can be easily adjusted.

20 Journaled in the bearings 29 and 29a which are mounted on the sides 17 and 18 respectively, of the housing 11, is a brush shaft 30 on which the 25 brush 31 is mounted for rotation therewith. The shaft 30 projects through the bearing 29 to accommodate a grooved pulley 32 which is fixedly mounted on said shaft and is adapted to rotate therewith.

30 The brush 31 comprises a cylinder 33 having end walls 34 provided with apertures 34a for mounting on the shaft 30. End members 35 provided with set screws 36 serve to position and secure the cylinder 33 on the shaft 30. Spacedly 35 mounted on said cylinder and secured by bolts 33a are a plurality of brush sections 37 having tempered steel bristles 38 secured in a suitable base 39. A brush of this construction not only provides a sweeping action but also a fan action 40 which serves to carry the sweepings well into the interior of the dirt collecting bin 40. It is apparent that any one brush section 37 may be removed and replaced without interfering with any of the other of said brush sections on the cylinder 45 33. Economy in maintenance of the machine is thus effected.

40 The dirt collecting bin 40 extends the full width of the machine and is shaped in cross section substantially as that shown in Fig. 3. The 50 bottom edge 40a of the bin 40 is provided with a flexible lip 41 which engages the floor and prevents scattering of the sweepings. Said bin is removably mounted on the machine and is supported on the transverse bar 15 and projecting 55

flange 16b of the arcuate shield 16. A coil spring 42 secured to an angle iron 43 of the engine mounting presently to be described is adapted to engage a lug 44 positioned on the bin 40 to retain same in position. Handles 45 mounted on the bin 40 facilitates the handling of same.

To perform a washing operation, the bin 40 is removed and a baffle plate 46 provided with handles 47 is positioned forwardly of the arcuate shield 16, as shown in Fig. 6. A tank 48 containing washing fluid is removably mounted on the machine and is supported on legs 49 which are adapted to rest on the transverse bar 15. Said tank is provided with an opening 50 for admitting fluid, and a discharge aperture 51 into which is fitted a valve 52 and discharge nozzle 53. Said nozzle is formed of an elongated cylindrical member 53a having a plurality of small openings 53b to permit the cleaning fluid to flow therethrough.

A rod 54 hingedly secured to a valve lever 55 is provided for manually regulating the flow of washing fluid through the discharge nozzle 53. An L shaped member 56 provided with a slotted portion 56a and pivotally mounted on an angle iron 57 secured to the tank 48 serves as a means for locking said tank on the machine. A spring 59 secured to the member 56 and to the angle iron 57 is adapted to maintain the slotted portion 56a in engagement with the angle iron 43 of the engine mounting.

Motive power to the brush 31 is supplied by a gasoline engine 58 which is positioned on a frame mounted on the housing 11. Said frame has two vertically mounted brackets 60 and 61 which are secured by bolts 61a to the arcuate shield 16 of the housing 11. Pivotally mounted on the bracket 61 are a pair of spaced angle irons 43 and 43a upon which is secured a plate member 62 which serves as a base for the engine 58. A cam member 63 provided with a lever 64 is rotatably mounted in the bracket 60 and is adapted to bear against the under side of the plate member 62 to serve as a means for taking up the slack of the driving belt 65. The driving pulley 66 is mounted on a shaft 67 journaled in a bearing 68 and coupled to the engine shaft 69 by means of a coupling 70.

The operation of the machine is apparent from a consideration of the following. By turning the adjusting wheel 27 the height of the brush with respect to the floor is easily adjusted. If the floor is particularly dirty the rear end of the machine is lowered by the adjusting wheel 27 to increase the pressure of the brush 31 on the floor. The lever 64 is moved to the left so that the high point of the cam 63 is moved out of engagement with plate 62. This action causes the pulley 65 to move downwardly and thus slacken up the driving belt 65. With the belt in slipping position the engine 58 is started in the conventional manner. To impart rotary motion to the brush 31 the lever 64 is shifted to the right so that the cam 65 is caused to raise the engine mounting. The slack of the driving belt 65 is thereby taken up and the brush 31 is caused to rotate with same. It will be remembered that during a sweeping operation the dirt collecting bin 40 is always positioned on the machine. As hereinbefore described, for a washing operation the bin 40 is removed and the baffle plate 46 and tank 48 is secured on the machine.

The cleaning fluid by reason of the positioning of the elongated discharge nozzle 53 is caused to flow evenly in front of the machine to provide for

higher efficiency in operation. The rate of flow is manually regulated by the rod 54.

It is apparent that when the machine is in operation as a washing machine the liquid is thrown against the baffle 46. The positioning of the baffle 46 is such that the liquid which strikes it is caused to be deflected towards the floor. There is therefore always a sufficient quantity of cleaning liquid on the floor area immediately preceding the brush.

The light weight of the machine makes it possible to be operated with very little effort by a single person. The simple and durable construction of the parts makes for low cost in operation and maintenance of same.

It is to be understood that the form of our invention herewith shown and described, is to be taken as a preferred example of the same, and that various changes in the shape, size and arrangement of parts may be resorted to, without departing from the spirit of our invention, or the scope of the appended claims.

We claim:

1. In a machine of the class described comprising a housing, a rotary brush in said housing, means for rotating said brush, said housing having an upper wall and forwardly extending side portions, a cross-bar mounted at the forward lower end of said side portions, the upper wall of said housing terminating rearwardly of said cross-member, and supporting means connected to said housing above and rearwardly of said cross-member, said means cooperating with said cross-member to form a support for interchangeably receiving a dust collecting bin or a fluid tank.

2. In a machine of the class described comprising a housing, a rotary brush in said housing, means for rotating said brush, said housing having an upper wall and forwardly extending side portions, a cross-member mounted at the forward lower end of said side portions, the upper wall of said housing terminating rearwardly and above said cross-member, and supporting means connected to said housing above and rearwardly of said cross-member, said means cooperating with said cross-member to form a support for interchangeably receiving a dust collecting bin or a fluid tank.

3. In a machine of the class described comprising a housing, a rotary brush in said housing, means for rotating said brush, said housing having an upper wall and forwardly extending side portions, a cross-member mounted at the forward lower end of said side portions, the upper wall of said housing terminating rearwardly of said cross-member, supporting means connected to said housing above and rearwardly of said cross-member, and a fluid tank removably supported on said supporting means and on the cross-member.

4. In a machine of the class described comprising a housing, a rotary brush in said housing, means for rotating said brush, said housing having an upper wall and forwardly extending side portions, a cross-member mounted at the forward lower end of said side portions, the upper wall of said housing terminating rearwardly of said cross-member, supporting means connected to said housing above and rearwardly of said cross-member, a fluid tank removably supported on said supporting means and on the cross-member, and a baffle plate removably supported on said cross-member and on a portion of said housing.
